UNITED STATES PATENT OFFICE.

CASEY SZAFRANSKI, OF SOUTH CHICAGO, ILLINOIS.

WIRE-CUTTING BAYONET.

1,266,640.

Specification of Letters Patent. Patented May 21, 1918.

Application filed February 11, 1918. Serial No. 216,554.

To all whom it may concern:

Be it known that I, CASEY SZAFRANSKI, a citizen of the United States of America, residing at South Chicago, in the county of 5 Cook and State of Illinois, have invented certain new and useful Improvements in Wire-Cutting Bayonets, of which the following is a specification.

The primary object of the invention is 0 the provision of a ready means carried by a gun for cutting wire entanglements and similar obstructions offered by the enemy to the line of march, the device being simple in construction and adding no material 5 weight to the fire arm provided therewith.

A further object of the invention is the provision of an attachment for the bayonet of a rifle for readily cutting wires when operated by the soldier or other person holding the gun in any usual manner, the operation 10 of the device being in the nature of shearing.

In the drawing forming a part of this application and in which like designating 15 characters refer to corresponding parts throughout the several views,

Figure 1 is a side elevation of the device mounted upon the barrel of a rifle.

Fig. 2 is a view similar to Fig. 1 with the 20 wire cutting member closed.

Fig. 3 is a view taken upon line III—III of Fig. 2.

Fig. 4 is a transverse sectional view taken 25 upon line IV—IV of Fig. 1.

Fig. 5 is a transverse sectional view taken 30 upon line V—V of Fig. 2, and

Fig. 6 is an enlarged fragmentary view 35 of the operating connections for the shearing blade.

It will be understood that my device may 40 be attached to the usual form of bayonets such as 10 and which bayonets provide opposite cutting edges 11 extending longitudinally thereof, while the bayonet 10 is adapt- 45 ed for rigid attachment to a gun barrel such as 12 by means of a bracket 13.

While my invention is primarily in the form of an attachment for the bayonet 10, it will be noted that the bayonet is a neces-

sary element as one of the edges 11 of the 50 bayonet assists in the cutting operation. A shearing blade 14 is pivoted as at 15 between opposite plates 16 secured to a flat shank portion 17 of the bayonet 10, the arrangement being such that the cutting edge 18 of 55 the blade 14 is positioned opposite the outer edge 11 of the bayonet 10 for co-operating therewith during the cutting operation when the blade 14 is pivotally moved upon its hinge 15. 60

An operating rod 19 is provided for the blade 14 being operatively attached by means of a link 20 to a curved rocker arm 21 pivoted as at 22 to the bayonet shank 17 and having a loose connection 23, of the 65 pin and slot variety, with the heel 24 of the said blade 14.

The rod 19 extends to any convenient point of operation adjacent the rifle, such for instance as a point adjacent the butt or 70 stock thereof, not shown, and the said rod 19 may be extended through a tubular guide 25 carried beneath the barrel 12 if found desirable. While carrying the gun provided with the bayonet 10, the cutting device will 75 be normally open with the blade 18 and the bayonet edge 11 separated as shown in Fig. 1 of the drawing. When it is desired to sever a wire such as 26, the wire is positioned between the cutting edges 11 and 18 80 while the rod 19 is pulled rearwardly in the direction indicated by the arrow in Fig. 2 of the drawing and this operation forces the blade heel 24 in a direction away from the bayonet 10 thereby forcing the edge 18 85 of the blade 14 toward the adjacent edge 11 of the bayonet 10 and cutting through the wire 26 positioned between the said edges. 90

The attachment herein described is light in weight and adds very little weight or 90 bulk of material to the ordinary form of gun barrel and bayonet while the device is always ready for instant use in cutting wire entanglements and similar barriers.

What I claim as new is:—

A device of the class described comprising in combination with a gun barrel having a bayonet mounted thereon and ar-

ranged with a flat shank adjacent the barrel, plates secured to said shank, a shearing blade pivoted to the said plates with a cutting edge arranged adjacent to and adapted for coöperating with the said bayonet during the cutting operation, a curved rocker arm pivoted to said shank operatively

connected to the adjacent heel portion of the blade, a tubular guide and an operating rod linked to the said arm and extending through the said guide.

In testimony whereof I affix my signature.

CASEY SZAFRANSKI.
